United States Patent Office

Des. 211,428

Patented June 11, 1968

211,428

LETTER TRAY

Thomas H. Davis, Rocky River, Ohio, assignor to The General Industries Company, Elyria, Ohio, a corporation of Ohio

Filed June 1, 1967, Ser. No. 7,331

Term of patent 14 years

(Cl. D74—9)

Fig. 1

Fig. 2

Fig. 3

Fig. 4

Fig. 5

Fig. 6

FIG. 1 is a perspective view of the letter tray showing my new design as seen partially from the front, left-hand side and top of the tray;

FIG. 2 is a left-hand side elevation view thereof;

FIG. 3 is a right-hand side elevation view thereof;

FIG. 4 is a top plan view thereof;

FIG. 5 is a front elevational view thereof; and

FIG. 6 is a rear elevational view thereof.

I claim:

The ornamental design for a letter tray, as shown.
